CLAIM

The ornamental design for a column depth measuring guide, as shown and described.

DESCRIPTION

FIG. 1 is a perspective view of the column depth measuring guide;

FIG. 2 is a second perspective view thereof;

FIG. 3 is a rear plan view thereof;

FIG. 4 is a front plan view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines are included for the purpose of depicting portions of the column depth measuring guide that form no part of the claimed design.
